UNITED STATES PATENT OFFICE.

LOUIS MARX, OF BROOKLYN, NEW YORK.

DESIGN FOR A FIGURE TOY.

Application filed February 20, 1926. Serial No. 16,618. Term of patent 3½ years.

To all whom it may concern:

Be it known that I, LOUIS MARX, a citizen of the United States, residing in Brooklyn, county of Kings, State of New York, have invented a new, original, and ornamental Design for a Figure Toy, of which the following is a specification, reference being had to the accompanying drawing, forming a part thereof, wherein—

What I claim is:

The ornamental design for a figure toy, as shown.

LOUIS MARX.
